UNITED STATES PATENT OFFICE.

THOMAS B. STEPHENSON, OF FORESTVILLE, CONNECTICUT, ASSIGNOR TO THE SESSIONS CLOCK COMPANY, OF FORESTVILLE, CONNECTICUT, A CORPORATION.

LOCKING DEVICE FOR DASH-CLOCKS.

1,137,032.

Specification of Letters Patent. Patented Apr. 27, 1915.

Application filed January 15, 1915. Serial No. 2,445.

To all whom it may concern:

Be it known that I, THOMAS B. STEPHENSON, a citizen of the United States, residing at Forestville, in the county of Hartford and State of Connecticut, have invented certain new and useful Improvements in Locking Devices for Dash-Clocks, of which the following is a specification.

My invention relates to improvements in locking devices for dash clocks, and particularly to means for locking a clock to a dashboard for automobiles, and the object of my improvement is simplicity and economy in construction and convenience 15 and efficiency in use.

In the accompanying drawing:—Figure 1 is a front elevation of a combination of a bezel of a clock and the adjacent parts and a supporting ring embodying my invention. Fig. 2 is a side elevation of the same. Fig. 3 is a rear elevation of the same. Fig. 4 is a side elevation of the bezel alone. Fig. 5 is a front elevation of the supporting ring alone. Fig. 6 is an inside view of a part of 25 the latch and adjacent parts. Fig. 7 is a front elevation on an enlarged scale and in part broken out of certain parts shown in Fig. 1. Fig. 8 is a similar view of the same with the parts moved to an intermediate position. Fig. 9 is a side elevation of part of 30 the same. Fig. 10 is a similar view with the parts in a different position.

The bezel 10 is an annular structure having means for receiving and supporting the 35 clock dial 11 and crystal 12 and for being connected to the body portion of the clock, and the bezel is receivable in the ring 13 that serves as a support therefor, and the said bezel and ring are locked together by my 40 improved locking device. The said bezel 10 comprises a flat annular body portion 14 having a plurality of holes 15 for engaging with the frame posts of the clock, the latter not being shown, and at the outer periphery of 45 the said body portion 14 there is a forwardly extending cylindrical flange 16, having at the extreme front edge portion an outwardly extending rim 17.

The dial 11 and crystal 12 are housed 50 within the cylindrical flange 16, and are secured in place by means that are ordinary. On the cylindrical flange 16 there is on one side, a radially directed pin 18, which is fixed and which serves as part of a bayonet joint connection for securing the bezel 10 to

the ring 13, the said pin 18 being on the right side of the clock as viewed from the front, as shown in Fig. 1, the same being shown at the left in the rear view Fig. 3. Diametrically opposite the radial pin 18 is 60 a radial latch pin 19 which extends through a hole 20 in the side wall of the said cylindrical flange 16 and is mounted by its inner end on a spring 21. The spring 21 is made of flat spring material, is curved to fit along 65 the inner face of the flange 16, and is secured by one end, shown as the lower end, to the said flange 16 in any ordinary manner, as by a rivet 22. A second radial pin 23 is also mounted on the spring 21, is positioned to one side of the latch pin 19, being shown as below the same and separated therefrom by a small space, and passes outwardly 70 through the hole 24 in the flange 16.

The supporting ring 13 comprises a flat 75 annular body portion 25 suitable for being mounted on the front face of a dashboard and having a central hole for admitting the body of the clock and having a cylindrical flange 26 extending forwardly from the inner edge of the said hole, and which is a fit for and suitable to receive the flange 16 on the bezel 10. The flange 26 on the ring 13 is provided on diametrically opposite sides 80 with similar bayonet slots 29 comprising the 85 longitudinally directed entrance portion 27 opening on the front edge, or extends from the said front edge rearwardly, and a laterally or circumferentially directed branch portion 28 connecting with the said entrance 90 portion 27 and directed therefrom as shown in the clockwise direction.

The manner of engagement and disengagement of the radial pin 18 at the right side and the corresponding bayonet slot 29 95 is ordinary, the pin being an operative fit for the said slot and the engagement being effected in the usual manner by a slight longitudinal movement, with the pin 18 in the entrance portion 27 of the slot and then a 100 turning movement of the bezel 10 in the clockwise direction relatively to the ring 13, and the release is effected by a reversal of the movement described.

On the left side the movable latch pin 19 105 serves as the pin of the bayonet joint on this side in engagement with the bayonet slot 29. The said latch pin 19 is of sufficient length to project through the hole 20 and slot 29 appreciably, in normal position, as 110

shown in Fig. 7, so that when the same is pushed inwardly the spring 21 will be pushed inwardly away from the wall of the flange 16. As the spring 21 is pushed inwardly as mentioned it carries with it the second pin 23, which latter is also engaged with the bayonet slot 29. The movement of the second pin 23 as described and the length of the same are such that the same will be brought below the level of the outer flange 26, thus freeing the same from engagement with the bayonet slot 29.

The circumferential separation of the two pins 19 and 23, which are mounted on the spring 21 is such that they fit in the circumferential branch 28 of the bayonet slot 29, as shown in Fig. 2, and when they are positioned therein as shown in the said figure, and also in Fig. 7 they coöperate to prevent relative rotative movement of the bezel 10 and the ring 13. In order to permit such rotative movement and the separation of the bezel 10 and ring 13 the latch pin 19 is depressed, thus freeing the second pin, or stop pin 23 from the slot 24, when such rotative movement will be permitted in the counter-clockwise direction until the latch pin 19 is brought into alinement with the entrance portion 27 of the bayonet slot 29, after which the bezel and ring are separated by a longitudinal movement, it being understood that during the movements described the pin 18 on the right side is disengaged from the corresponding bayonet slot 29.

In order to reassemble the parts the latch pin 19 is depressed, and is entered into the entrance portion 27 of the bayonet slide 29 until in line with the lateral branch 28, and the hold on the latch pin 19 is released, permitting the second stop pin 23 to bear against the under side of the flange 26. Turning the bezel clockwise to the limit permitted by the latch pin 19 engaging with the end wall of the branch portion 28 of the bayonet slot brings the stop pin 23 within the limits of the slot, and the same is then forced forwardly by the spring 21 into engagement with the said slot.

As described, there are two pins mounted on the latch spring 21 one of these, the latch pin 19, serving as the pin that coöperates with the bayonet slot 29 in operating as the bayonet connection or joint, and the other pin, the stop pin 23, serves in coöperation with the other pin 18 to lock the parts against rotative movement.

It will be noted that the latch pin 19 which serves as a push pin to unlock the

bezel or sash 10 from the supporting ring or frame 13 serves for the double purpose 60 of a lock and a push pin.

I claim as my invention:—

1. A bezel and a supporting ring therefor, the said bezel having a cylindrical flange, the said ring having a flange portion 65 fitting over the said flange and provided with a bayonet slot composed of a longitudinally directed entrance portion and a lateral branch connected with the said entrance portion, a spring mounted by one end on the 70 inner face of the said cylindrical flange, a pair of pins mounted on the other end of the said spring, and suitably spaced to fit in the said lateral branch, the said other end having an inward movement sufficient to release one of the said pins from the said slot, and the other of the said pins being longer than the said first pin suitably to serve as an operating knob for effecting such movement of the said spring and the said pins 80 being so arranged that when they are engaged with the said lateral branch of the bayonet slot the pin that serves as an operating knob will be out of alinement with the said entrance portion, whereby the said 85 last named pin throughout the range of movement for effecting the release of the mating pin will be positively engaged with the said lateral portion.

2. A circular sash for a clock face member, an annular supporting frame therefor, the said sash and frame having overlapping sleeve portions, one of the said sleeve portions having a bayonet slot comprising a longitudinally directed entrance portion and a laterally directed branch, a spring mounted on the other of the said sleeve portions, a pair of pins mounted on the said spring in spaced relation to fit in the said lateral branch, one of the said pins being short, 100 suitably to be brought out of engagement with the said slot when the said spring is depressed and when in locking position being at the end of the said lateral branch adjacent the said entrance portion, and the 105 other of the said pins being positioned out of alinement with the said entrance portion and being of sufficient length to remain in engagement with the said lateral branch throughout the necessary movement for 110 effecting the release of the said short pin.

THOMAS B. STEPHENSON.
